(57) **CLAIM**

The ornamental design for a display panel for an electronic still camera, as shown and described.

DESCRIPTION

FIG. 1 is a top, front and side perspective view of a display panel for an electronic still camera, showing my new design; FIG. 2 is a front elevational view thereof; and, FIG. 3 is an enlargement of a portion of FIG. 2.

The broken line representation of an electronic still camera forms no part of the claimed design and is shown only to illustrate the environment of the device whose design is claimed.
